UNITED STATES PATENT OFFICE.

FREDRICK C. ECKHARDT, OF NORTH WALES, PENNSYLVANIA.

DESIGN FOR A HAT.

SPECIFICATION forming part of Design No. 29,006, dated July 5, 1898.

Application filed May 21, 1898. Serial No. 681,378. Term of patent 31 years.

To all whom it may concern:

Be it known that I, FREDRICK C. ECKHARDT, a citizen of the United States, residing at North Wales, in the county of Montgomery, 5 State of Pennsylvania, have invented and produced a new and original Design for Hats, of which the following is a specification, reference being had to the accompanying drawings, forming part thereof.

Figure 1 is a side elevation of a hat embodying my new design. Fig. 2 is a plan view showing the under side. Fig. 3 is a sectional view taken on the line *a a* of Figs. 1 and 2.

As shown in the accompanying drawings, 5 the leading or material features of my design, as seen in side elevation, are embodied in the lines of a battle-ship as they appear above the water-surface, including a spar-deck 1, forming the top or crown of the hat, a main deck 2, and a hull 3, while a plan view of the

under side shows the part 3 to be of elliptic section, having the apices of the curve drawn out to the points 4 and 5, with the ellipse or oval 6 internally tangent thereto, as the contour of the crown.

The side of the hat shows in outline the turret 7, the gun 8, the funnels 9 and 10, the boats 11, and davits 12, the masts 13, and flags 14. Where such features appear above the decks, they are in the same plane 15, as 25 30 illustrated in Fig. 3.

Having described my invention, I claim as new and desire to secure by Letters Patent—

The design for a hat, as herein shown and described.

FREDRICK C. ECKHARDT.
